UNITED STATES PATENT OFFICE

2,261,358

PICKUP FOR ELECTRICAL STRINGED
MUSICAL INSTRUMENTSWalter L. Fuller, Kalamazoo, Mich., assignor to
Gibson, Inc., Kalamazoo, Mich., a corporation
of Michigan

Application March 18, 1940, Serial No. 324,461

3 Claims. (Cl. 84—1.15)

This invention relates to improvements in pickups for electrical stringed musical instruments.

The main objects of this invention are:

First, to provide an improved magnetic pickup for electrical reproduction of the playing of stringed instruments which is compact and effective in operation.

Second, to provide a pickup of the type described which is readily applicable to and detachable from stringed musical instruments of various types.

Third, to provide a pickup which can be mounted on or removed from an instrument with a minimum of difficulty and which in mounted position thereon does not detract from the appearance of the instrument or handicap the playing thereof in the usual manner.

Further objects of my invention will appear from the description to follow. The invention is 20 defined in the claims.

A structure embodying the features of my invention is illustrated in the accompanying drawing, wherein:

Fig. 1 is a top view illustrating an instrument with the pickup of my invention applied thereto.

Fig. 2 is a perspective view illustrating the general appearance of the pickup with the instrument in a position assumed thereby when mounted on the instrument, which is indicated in dotted lines.

Fig. 3 is a fragmentary view in section on line 3—3 of Fig. 4, illustrating the construction and arrangement of the parts of the pickup and the relation thereof to the strings of the instrument.

Fig. 4 is a fragmentary perspective view in section on line 4—4 of Fig. 3, further illustrating details of the pickup.

Figs. 5 and 6 are perspective views illustrating the pickup mounting in other modified embodiments contemplated by my invention.

The present invention relates to a magnetic pickup which is readily attachable to and detachable from a stringed musical instrument such as a guitar, mandolin, or the like, being adapted to be effectively mounted on the exterior thereof in a simple manner so as to convert the conventional sound box bodied instrument into one for electrical amplification. To this end the device to be hereinafter described is simple, compact in its parts, and may be readily applied and removed, and does not detract from the appearance of the instrument when in operative position thereon. Another aspect of the invention

resides in the details of construction of the pickup per se which render the same highly effective in operation though exceedingly compact in form. A still further and highly important feature is to provide a device having these advantages which does not interfere with or handicap the player.

Referring to the drawing, reference numeral 1 indicates a guitar type instrument on which the pickup of my invention, generally designated 2, is mounted. This pickup comprises a housing or case 3 which is open at one end and has secured in the open end an insulated outlet block 4 affording a pair of connector sockets 5 for the reception of the prongs of a plug 6 on a cord 7 by which the pickup is connected to a suitable amplifier. A jack 8 is disposed on the other end of the cord for this purpose.

The socket connections 5 are connected to the ends of a coil 9 of fine wire, which is wound around an elongated laminated metal core 10 encased in suitable insulating material 11. The thus constituted elongated coil is disposed in the bottom half of the casing 3 and above the same 15 I place an elongated magnetic bar 12. The coil and bar extend practically the entire length of the case 3, as illustrated in Fig. 3, and are disposed beneath the strings 13 of the instrument in such manner that the variation in the intensity of the magnetic field of the magnet, conventionally indicated by the dotted lines 14 in Fig. 4, sets up small electrical currents in the coil which are transmitted by the cord 7 to the amplifier and magnified therein. The amplifier is connected to a suitable loud speaker in a manner which will be appreciated by those skilled in the art.

In order to enable the pickup to be readily mounted on the instrument, I secure the above 20 described casing to a flexible fibrous or cloth strap 15, utilizing prongs 16 spot welded on the bottom of the housing or case 3 for this purpose. If desired, a protective strip of felt or other material 17 may be secured beneath this strap so as to avoid any likelihood of scratching or marring the finish of the instrument. A suitable buckle 18 attached to the strap enables the same to be fitted to an instrument of any type or size. Thus, in Fig. 1, I show the pickup attached to a guitar type instrument at the narrowest part of the girth thereof, i. e., between the bridge and fret arm, and it will be appreciated that it may be similarly attached to any instrument.

In Fig. 5, I illustrate a modified embodiment 25 of my invention, wherein the pickup 2 is spot

welded to a bar 19 carried on a wire rod adjusting arm 18. A clip 20 is adjustably slidable and securable with relation to arm 18 in order to permit the desired spacing of the pickup lengthwise of the strings and I contemplate that this clip be removably attachable to the bridge of the instrument utilizing a wing nut 21 thereon for this purpose.

In the modification of Fig. 6, the pickup 2 is attached to the medial point of a clip member 22 which has a forked end provided with spring arms 23. One of these arms may be inserted in the tone hole of an instrument having such a tone hole directly beneath the strings thereof, the arms 23 frictionally gripping the wood of the top surface or panel of the instrucent body. The other extremity 24 of the clip 22 is bent so as to rest on the instrument body at the opposite side of the tone hole from that with which the arms 23 are frictionally engaged. The pickup 22 is spot welded to a cross bar 25 in such manner as to be disposed beneath and extend transversely of the strings.

In each of the above described modifications, the pickup unit is per se the same, the mounting means therefor only varying, depending upon the type of attachment or the type of instrument with which it is employed. I find that a pickup similar to that illustrated in Figs. 3 and 4 is extremely sensitive since the disposition of the magnet 12 above and over the two sides of the elongated coil 11 provides the same effect as two magnets with the lines of force as indicated. The slightest vibration of the strings is effective to set up currents in the coil which are faithfully representative in their intensity of the vibration occurring in the string, whether it be bass or treble. The whole unit is exceedingly compact and proof against damage by mistreatment. It may be assembled and removed in an instant and, being quite inexpensively produced, is available widely to convert the conventional instrument for electrical reproduction in a second's time.

I have illustrated and described my improvements in embodiments which are very practical. I have not attempted to illustrate or describe other embodiments which I contemplate as it is believed this disclosure will enable those skilled in the art to adapt my invention as may be desired.

Having thus described my invention what I claim as new and desire to secure by Letters

10 Patent is:

1. In an electrically amplified stringed musical instrument having a bridge and a pickup disposed transversely of the strings, means for adjustably mounting the pickup on the instrument for adjustment longitudinally of the strings, comprising a clip removably engageable with the bridge of the instrument, an arm extending longitudinally of the strings and secured to the pickup, and means for adjustably securing said arm to the clip to variably position the pickup longitudinally of the strings.

2. In an electrically amplified stringed musical instrument having a bridge and a pickup disposed transversely of the strings, means for adjustably mounting the pickup on the instrument for adjustment longitudinally of the strings, comprising a support removably engageable with the instrument, an arm extending longitudinally of the strings and secured to the pickup, and means for securing said arm to the support in different positions of the pickup longitudinally of the strings.

3. In an electrically amplified stringed musical instrument having a pickup disposed transversely of the strings, means for adjustably mounting the pickup on the instrument for adjustment longitudinally of the strings, comprising a support having means for removably securing the same to the instrument, an arm extending longitudinally of the strings, and means for securing said arm to the support and pickup, said last named means including means for adjusting the pickup longitudinally of the strings.
